UNITED STATES PATENT OFFICE.

WILLIAM DUBILIER, OF NEW YORK, N. Y., ASSIGNOR TO DUBILIER CONDENSER CORPORATION, A CORPORATION OF DELAWARE.

HIGH-POTENTIAL CONDENSER.

Application filed March 7, 1919. Serial No. 281,183.

The invention relates to condensers adapted to withstand the conditions of use which are met with in high frequency or high potential circuits, for example in wireless 5 sets, and has for an object so to construct a condenser as to minimize the liability of breakdown or failure of insulation in use, and yet to avoid the necessity of employing a large amount of insulating material in 10 accomplishing this result.

Another object is to provide a condenser in which the conducting elements are effectively compressed to hold them in proper relation to each other, and in such manner 15 as to insure that the pressure will be evenly applied when the condenser is assembled, and properly maintained during use thereof.

Further objects and advantages will be 20 in part obvious and in part specifically mentioned in the description hereinafter contained, in which is disclosed one embodiment of the invention; such embodiment however, is to be considered merely illustrative of its principle. In the drawings,

Fig. 1 is a central vertical section of a condenser made in accordance with the invention, the section being taken on line 1—1 of Fig. 2.

Fig. 2 is a section taken on line 2—2 of 30 Fig. 1, looking in the direction of the arrows, and

Fig. 3 is a view similar to Fig. 2 but showing a modification of the compression members.

A casing 1, of any convenient shape, is 35 provided, which is ordinarily made of metal, and forms a ground connection for one terminal of the condenser. A plurality of condenser sections 2 are contained within 40 the casing, each section preferably comprising a plurality of interleaved conducting plates of opposite polarity, as is well known in the art. In order to facilitate the insulation of the condenser units which are to 45 be subjected to high potential strains in use, the several units are so disposed and related to each other, that the low potential units are interposed between the high potential units and points to which a breakdown 50 might occur. In the present instance, the condenser sections are connected into sets 3 and 4, the sections of each set being in series, and the sets being connected in parallel. The two sets are assembled to form a 55 block with the low potential units adjacent

and connected to walls of the casing, by connections 5, and the high potential units joined by a connection 7 which leads to any suitable terminal, for instance a post 8, mounted on an insulating cover 9 for the 60 casing.

If the condenser were made merely of a plurality of units connected in series, the potential of course from one end would rise progressively to the other, and the high potential end or unit would require special construction and a large amount of insulating material, to insulate it properly from the casing, or other adjacent metallic bodies connected to the casing. With the low potential units disposed at the ends of the block, however, the units adjacent to walls of the casing are at substantially the same potential as the casing, and no large potential strains are encountered at such points. Also 70 the high potential units naturally fall within the central or intermediate portion of the casing, and are spaced as far as possible therefrom, so that the insulation required is correspondingly small, and the high potential terminal connection may be lead out with minimum danger of a failure of insulation. In the present embodiment, merely a strip of insulation 10 is placed between the central portion of the condenser block, and 75 the walls of the casing. The term "high potential" as applied to certain of the condenser units in the specific type of condenser disclosed, is intended to mean those units 80 between which and surrounding members such as the clamp or casing, a potential difference exists; or those units 85 which are at or near the potential of terminal 8 which is highly insulated from the remainder of the structure. The term "low potential" of course has the opposite meaning.

In condensers of the types above described, it is desirable that clamping members be employed, of such character that 100 pressure can be effectively applied and maintained to hold the condenser units in proper relation to each other, and for this purpose, metallic clamping elements are the most efficient and durable. If the condenser be 105 made merely of a plurality of units connected in series, the use of metallic clamping elements held firmly with metallic parts, is difficult, owing both to the fact that the high potential end of the block must be 110

highly insulated and spaced from metal parts, and to the fact that intermediate metallic elements extending between the high and low potential ends of the block, 5 would be undesirable. Insulating material has therefore been used to compress condensers of the above character, but such material is disadvantageous in that it deteriorates and weakens when put under stress other than 10 compression in use, as is well known in the art. With condensers constructed in accordance with this invention, however, the end unit or units of the condenser block are at substantially the same potential as the 15 metal clamp, which potential also may be very low, and thus metallic clamping elements may safely be employed.

In the present embodiment, a metallic compressor member 11 is used, having a flat 20 bearing surface which engages one end face of the condenser block, and a similar compressor member 12, which may be integral with the opposite side wall of the casing provides a similar bearing surface for the 25 other end of the block. Preferably also, a single binding screw 13 is used, which engages the compressor member 11 at a point substantially in line with the center of the block of condenser units. If the pressure 30 be applied along an axial line with regard to the condenser, the member 11 will be permitted to accommodate itself to the natural shape of the block, and it will be insured that all portions of the condenser 35 are subjected to substantially the same pressure, which will not tend to distort or warp the units or compressor members.

As appears from Figs. 1 and 2, the compression on the stack or block acts between 40 the opposite end walls of the casing, and the side walls thereof act as integral metallic tension members connecting the end walls. Thus the casing as a whole acts in effect as an integral metallic clamp extending 45 from one compressor member 12 entirely around the other compressor member 11, providing a rigid structure which will be effective to maintain the proper compression on the stack.

50 The particular clamping device disclosed is not essential, but it has the further advantage that the condenser may be impregnated, if desired, in situ, thus avoiding any handling of, or tampering with the 55 units after being compressed and filled with wax compound, which handling is liable to result in injury or dislocation of the units.

In Fig. 3 is shown a construction in which 60 the compression of the condenser units is not dependent upon the casing. As shown, a plurality of condenser units, preferably assembled into a block composed of sets 3 and 4 of condenser sections as previously described, and disposed parallel to side 65 walls of the casing, are engaged by com-

pressor members 14 and 15, which abut the end of the block, suitable binding members such as bolts 16, being used to draw the compressor members together. If desired, the compression may be applied at a point 70 substantially in line with the center of the block, by interposing plate 17 between the compressor member 14 and the end unit of the block, such plate being provided with a projection 18 in line with the center of the block, which cooperates with a similar recess in the compressor member.

With a construction of the type shown in Fig. 3, the condenser units may be assembled and put under compression before being 80 placed in the casing, or removed from the casing without releasing the compression. In the manufacture of condensers, it is customary to impregnate the same with a wax composition while the units are under compression, and with a condenser of the character shown in Fig. 3, it is possible to employ the compressor members 14 and 15 for the purpose of supplying the necessary 85 compression for the impregnating treatment, and then place the sections in final position within the metallic casing, without disturbing them after impregnation.

If sets of sections connected in parallel 90 be employed, the compression members 14, 15, and the bolts 16, may all be of metal and uninsulated from each other or from the casing, since all of these parts will be at the same potential when in use. If desired, insulating strip 19, similar to the strip 10 previously described, may be interposed between the central portion of the condenser block, and the adjacent metallic parts.

While a specific form of the invention has 100 been described, it will be obvious that many changes may be made without departing from its spirit, as defined in the following claims.

What is claimed is:—

1. A high potential condenser comprising 110 a metallic casing, a plurality of sets of condenser units therewithin said sets being connected in parallel, each of said sets comprising a plurality of condenser units connected 115 in series, the high potential units of each of said sets being disposed in the central portion of the casing, and the low potential units being disposed adjacent to walls of said casing.

2. A high potential condenser comprising 120 a metallic casing, a plurality of sets of condenser units therewithin said sets being connected in parallel, each of said sets comprising a plurality of condenser units connected 125 in series, the high potential units of each of said sets being disposed in the central portion of the casing, and the low potential units being disposed adjacent and electrical- 130 ly connected to walls of the casing.

3. A high potential condenser comprising condenser units juxtaposed in line with each other to form a block, the high potential units being located in the intermediate portion of the block, and units on opposite sides of such high potential units being respectively in series whereby the potential decreases progressively through a substantial number of units from the high potential units toward the opposite ends of the stack, a unit of lowest potential being located between the high potential units and one end face of the stack.
4. A high potential condenser comprising a plurality of juxtaposed condenser units of stepped potential assembled to form a block, units of low potential being located at the outer portions of the block and all the units of any substantial higher potential in the inner portion of such block.
5. A high potential condenser comprising two sets of condenser units connected in parallel, each of said sets comprising a plurality of units connected in series, said sets being assembled to form a block with the high potential units at its central portion and the units of lowest potential adjacent its end faces.
6. A high potential condenser comprising a plurality of condenser elements of stepped potential assembled to form a block, the units of said block at both its ends being at low potential in use, metallic compressor members respectively engaging said end units, and means for compressing the condenser between said members.
7. A high potential condenser comprising a metallic casing, a plurality of sets of condenser units therewithin connected in parallel, each of said sets comprising a plurality of condenser units connected in series, the high potential units of each of said sets being disposed in the central portion of the casing, and the low potential units being disposed adjacent and electrically connected to walls of the casing, metallic compression members being provided to engage the low potential units and hold the condenser in shape.
- 50 8. A high potential condenser comprising a casing, a plurality of sets of condenser units therewithin connected in parallel, each of said sets comprising a plurality of condenser units connected in series, the high potential units of each of said sets being disposed in the central portion of the casing, and the low potential units being disposed adjacent to walls of said casing, and means for exerting pressure upon the low potential units to hold the condenser in shape.
9. As an article of manufacture, a high potential condenser comprising a plurality of condenser units assembled to form a block, each of said units being made up of flat dielectric and conducting sheets, com-
- pressor members engaging end faces of said block, and a bearing member within the casing engaging one of said compressor members at a point substantially in line with the center of the block to exert pressure upon the condenser and maintain the sheets in substantially flat condition.
10. As an article of manufacture, a high potential condenser comprising a metallic casing, a plurality of condenser units disposed within said casing substantially parallel to side walls thereof each of said units being made up of flat dielectric and conducting sheets, a compressor member located between an end unit of said condenser and the adjacent side wall of the casing, and a bearing member comprising a screw passing through such side wall and engaging said compressor member at a point substantially in line with the centers of said units to compress the condenser toward the opposite side wall of the casing and maintain the sheets in substantially flat condition.
11. A high potential condenser comprising a metallic casing, a condenser therewithin comprising a plurality of condenser units substantially parallel to side walls of such casing and assembled to form a block, units of low potential being located adjacent opposite side walls of the casing the units of highest tension being located in the intermediate portion of the block, a metallic compressor member between one of said side walls and the adjacent end condenser unit, and means for exerting pressure on said member to compress the condenser toward the opposite side wall of the casing.
12. A high potential condenser comprising a plurality of condenser elements of different potentials assembled to form a block, wherein substantially all the low potential elements are disposed on different sides of the high potential elements to act as separators between the high potential elements and the end faces of the block.
13. As an article of manufacture a high potential condenser comprising a boxlike metallic casing, a block of condenser units disposed within said casing with the units substantially parallel to side walls of the casing, said block including units connected in series, and means for utilizing side walls of said casing to transmit compression to opposite faces of said block.
14. As an article of manufacture a high potential condenser comprising a boxlike casing, a block of condenser units disposed within said casing with the units substantially parallel to opposite walls of the casing, said block including units connected in series, and means applying expansive force between a face of said block and the adjacent wall of said casing for exerting effective compression upon said units.
15. As an article of manufacture a high

potential condenser comprising a boxlike casing, a block of condenser units disposed within said casing with the units substantially parallel to opposite metal walls of the casing, said block including units connected in series, and an adjustable force applying member projecting through one wall of said casing and bearing against the adjacent end of the block for exerting compression upon said units.

16. As an article of manufacture a high potential condenser comprising a boxlike metallic casing, a plurality of condenser units disposed within said casing substantially parallel to opposite walls thereof and assembled to form a block, the high potential units of the block being disposed in the intermediate portion thereof and each of the end units of said block being substantially at the same potential as the walls of said metallic casing when the condenser is under electric stresses.

17. As an article of manufacture a high potential condenser comprising a boxlike metallic casing, a plurality of condenser units disposed within said casing substantially parallel to opposite walls thereof and assembled to form a block, the high potential units of the block being disposed in the intermediate portion thereof and each of the end units of said block being substantially at the same potential as the walls of said metallic casing, and means for utilizing other walls of said casing to transmit mechanical compression to the opposite faces of said block.

18. As an article of manufacture a high potential condenser comprising a boxlike metallic casing, a plurality of condenser units disposed within said casing substantially parallel to side walls thereof, and assembled to form a block, the high potential units of the block being disposed in the intermediate portion thereof and said block including units connected in series, and means comprising metallic members engaging opposite faces of said block for exerting compression upon said units, said casing being provided with a cover, and a high potential terminal for said block being provided on said cover.

19. As an article of manufacture, a high potential electrical condenser comprising a block of condenser sections, and clamping means for extending a relatively high pressure on said block, said clamping means comprising a metallic casing having integral end and side walls, the end walls being opposed to opposite faces of the block, and the side walls acting as tension members between said end walls and holding the latter in proper relationship.

20. A high potential condenser comprising a boxlike metallic casing, a block of condenser sections disposed within said casing substantially parallel to side walls thereof

whereby the edges of the sections are exposed to the open side of the casing, said block including sections connected in series and a high potential section being located in the inner portion of said block, sections of lower potential being disposed on opposite sides of the high potential section, a cover for said casing, a high potential terminal mounted in said cover and insulated from said casing, and a connection leading from said high potential section to said terminal.

21. A high potential condenser comprising a plurality of condenser units of stepped potential assembled to form a block, a unit of high potential being located in the inner portion of said block, with permanent electrical connections whereby the end units of said block are substantially at the same potential in use, and metallic clamping means for exerting a relatively high compression upon the end faces of said block.

22. As an article of manufacture, an electrical condenser having a stack of condenser elements, and clamping means for exerting a relatively high pressure upon said stack, said clamping means comprising an integral metallic member extending entirely around the stack, a compressor member adapted to exert pressure on one end face of the stack, and means acting between said compressor member and the adjacent portion of said integral metallic member, for exerting compressive force on said compressor member to compress the stack within said integral metallic member.

23. A high potential series parallel condenser consisting of a stack of condenser sections, with a terminal lead from a mid-point of the stack; metallic clamping means in compressing engagement with the ends of the stack; and a terminal electrically connected with said stack ends.

24. A sheet condenser comprising a stack of serially connected sections, an all-metal clamp engaging the ends of the stack to hold it under compression, and a metal casing for the stack and clamp, one terminal of the stack leading from approximately a mid-point thereof.

25. A high potential condenser having a metallic clamp, a plurality of sets of condenser units surrounded thereby, said sets being connected in parallel, and said sets comprising units connected in series, the outer end units of said sets which are disposed adjacent said metallic clamp being at substantially the same potential as the latter when the condenser is subjected to electrical stress, and the units of opposite potential being separated from the clamp by said outer units.

26. A high potential condenser comprising a stack of condenser units, sets of said units being connected in parallel and the units of said sets being connected in series,

the end units of the stack being at substantially the same potential when the condenser is subjected to electrical stress, and a metallic clamp surrounding said stack and bearing upon end units thereof, said clamp being substantially spaced from intermediate units of the stack.

27. A high potential condenser having series connected units and circuit connections whereby the end units of the stack are at substantially the same potential when the condenser is subjected to electrical stress, and a metallic clamp surrounding said stack and bearing against the end units thereof, the sides of the clamp being substantially spaced from intermediate units of the stack.

28. An electrical condenser, comprising a stack having series connected units, a housing completely enclosing said stack and having walls of insulating material and metal respectively, at least two of said walls being of metal and facing each other, the ends of the stack lying parallel to and adjacent said above mentioned facing metal walls, and

25 means alined with the stack for clamping it end to end between said facing metal walls.

29. An electrical condenser, comprising a stack having series connected units, a housing completely enclosing said stack and having walls of insulating material and metal respectively, at least two of said walls being of metal and facing each other, the ends of the stack lying parallel to and adjacent said above mentioned facing metal walls, and clamping means located between one end of the stack and the adjacent metal wall for compressing the stack in a direction towards the oppositely facing metal wall.

30. An electrical condenser, comprising a stack having series connected units, a hous-

ing completely enclosing said stack and having walls of insulating material and metal respectively, at least two of said walls being of metal and facing each other, the ends of the stack lying parallel to and adjacent said above mentioned facing metal walls, a compression plate interposed between one end of the stack and the adjacent metal wall and a screw in said wall bearing on said plate to compress the stack.

31. An electrical condenser, comprising a stack having series connected units, a housing completely enclosing said stack and having walls of insulating material and metal respectively, at least two of said walls being of metal and facing each other, the ends of the stack lying parallel to and adjacent said above mentioned facing metal walls, and means alined with the stack for clamping it end to end between said facing metal walls, said facing metal walls acting as compression members in clamping the stack and others of said first mentioned walls acting as tension members in clamping the stack.

32. An electrical condenser, comprising a stack having series connected units, a housing completely enclosing said stack and having walls of insulating material and metal respectively, at least two of said walls being of metal and facing each other, the ends of the stack lying parallel to and adjacent said above mentioned facing metal walls, means alined with the stack for clamping it end to end between said facing metal walls, and electrical connections between the end units of the stack and the adjacent metal walls.

In testimony that I claim the foregoing, I have hereunto set my hand this 21st day of February, 1919.
